UNITED STATES PATENT OFFICE.

PHILIP H. NOLTING, OF JERSEY CITY, NEW JERSEY.

WATCH HOLDER.

Application filed January 4, 1923. Serial No. 610,612.

To all whom it may concern:

Be it known that I, PHILIP H. NOLTING, a citizen of the United States, and a resident of Jersey City, in the county of Hudson and State of New Jersey, have invented new and useful Improvements in Watch Holders, of which the following is a full, clear, and exact description.

This invention relates to containers for attaching in pockets or the like for receiving articles that it is desired to store in the pockets, and was primarily designed for containing watches.

If a watch is carried in the pocket without being attached to the garment by means of a chain or other similar means there is great danger of dropping the watch out of the pocket when the garment is being taken off or put on. Also in stooping over, while working or exercising, the watch is likely to slide out of the pocket and receive great damage in its fall to the earth.

The general object of this invention is the provision of a simple and efficient device for attaching in a pocket to receive a watch or other similar article to retain the same in the pocket.

This object is accomplished by providing a casing of resilient material shaped to contain a watch, having an opening cut in one side for allowing the insertion of the watch into the casing, provided with means adjacent the opening for gripping the watch stem to hold it against movement, and fixing on the casing means for attaching it to a fabric.

This and other objects of the invention will be more clearly understood from the following detailed description and accompanying drawings.

Figure 1 is a top plan view of the watch protector;

Figure 2 is a bottom plan view of the watch protector showing the means for attaching it in a pocket;

Figure 3 is a side elevation of the watch protector showing the means for gripping the watch stem to hold the watch against movement;

Figure 4 is a view, showing the protector positioned in a pocket with a watch partially inserted into the same;

Figure 5 is a section through the watch

protector, showing it placed in a pocket and containing a watch.

Referring to the above-mentioned drawings, the invention includes two dish-shaped members 10 and 11 having rims 12 and 13, respectively. Portions of the rims 12 and 13 are cut away at 14 and 15, respectively. The dish-shaped sections 10 and 11 are then placed together, facing one another, with the rim of section 11 fitting into the rim or section 10 and the cut-away portions in alignment forming an opening 25. The rims of these sections are then fastened together in any satisfactory manner as by the use of glue, shown at 22 in Figure 5. The casing formed by placing these sections together is shaped to contain a watch, and the opening 25 is of such a size that a watch 23 may be inserted through the same into the casing. Usually the casing would be made from some material such as celluloid so that the walls are resilient to facilitate the insertion of the watch.

Notches 16 and 17 are cut in the rims of the sections 10 and 11, respectively, leaving projections 18 and 19 between them and the opening 25. These notches 16 and 17 register with one another, forming an opening. When the watch has been placed in the casing it is rotated, swinging the stem 24 between the projections 18 and 19. Since the walls of the casing are resilient the stem may be passed between the projections without any trouble. In order to attach the casing in the pocket a safety pin 21 is projected under a strap 20 raised from the wall of the section 10.

Referring to Figure 4, the casing is shown fastened in a pocket 26. A watch 23 is shown partially projected through the opening 25. After the watch has been projected completely into the casing it is rotated to the right, as shown by the dotted lines, carrying the stem 24 between the projections 18 and 19. These projections serve to lock the watch against movement in the casing. Many different constructions of this device might be made and some might be constructed with a lining to protect the watch from the wall of the container.

I would state in conclusion that while the illustrated example constitutes a practical embodiment of my invention, I do not limit

myself strictly to the exact details herein illustrated since manifestly the same can be considerably varied without departing from the spirit of the invention as defined in the 5 appended claims.

Claims:

1. A watch protector of the character described made of resilient material, comprising two dished sections having rim portions 10 presenting opposed cut-outs, said sections facing inward with the cut-outs in alignment and fixed together forming a casing, said cut-outs forming an opening for allowing the insertion of a watch, means adja- 15 cent one end of said opening for gripping the watch stem to hold it against movement,

and means attached to one of the sections for fastening the casing in a pocket.

2. A watch holder of the character described, comprising a casing having resilient 20 walls shaped to contain a watch and having an opening cut in its side for allowing the insertion of a watch, oppositely disposed projections on the sides of the casing near one end of said opening for gripping the 25 watch stem to hold it against movement in the casing, the edges of the casing adjacent to said projections presenting opposed notches to accommodate a watch stem and means carried by the casing for attaching 30 it in a pocket.

PHILIP H. NOLTING.
